INNERSOLE

Jimmy F. Cleghorne, Nashville, Tenn., assignor to Genesco, Inc., Nashville, Tenn., a corporation of Tennessee

Filed May 5, 1960, Ser. No. 60,455

Term of patent 14 years

(Cl. D7—5)

FIG. 1

FIG. 2

I claim:

The ornamental design for an innersole, as shown and described.
